UNITED STATES PATENT OFFICE.

EDWIN C. WORNS, OF RUTHERFORD, NEW JERSEY.

TOOL.

1,142,473.

Specification of Letters Patent.

Patented June 8, 1915.

Application filed May 2, 1913. Serial No. 765,033.

To all whom it may concern:

Be it known that I, EDWIN C. WORNS, a citizen of the United States, and a resident of Rutherford, in the county of Bergen and State of New Jersey, have invented a new and Improved Tool, of which the following is a full, clear, and exact description.

The object of my invention is to provide an improved tool adapted to be employed as 10 a scraper, or an ironing tool by furriers, for scraping the fat from the furs, and for ironing down a seam, in order to perform operations now requiring a scraper and a separate ironing device.

15 It is a further design of my invention to provide a more efficient scraper for use by furriers, and furthermore, to provide a tool adapted for general use as a scraper by paper hangers, for removing paper from the 20 walls, and for other purposes.

The invention will be particularly explained in the specific description following.

Reference is to be had to the accompanying drawings forming a part of this specification, in which similar characters of reference indicate corresponding parts in all the 25 views.

Figure 1 is a perspective view of a tool embodying my invention; showing the same 30 in position for use; Fig. 2 is a plan view of the tool; and Fig. 3 is a vertical longitudinal section.

The improved tool comprises a body 10, adapted to be grasped in the hand of the 35 user, and consists of a top 12, a bottom 11, a back 13, and a blade 14. The ends of the device are preferably closed as indicated at 10^a. The body has a width to extend at least the full width of the hand of the user, with 40 the back or rear end 13 pressed firmly against the palm of the hand, with the thumb on the under side against the body 11, and the four fingers gripping the top 12.

The bottom 11 presents a straight flat 45 surface, while the top 12 inclines forwardly from the rear thickened end of the body to the front and is curved longitudinally. The back 13 is rounded, curves vertically and merges in rounding lines into the bottom and 50 top. The blade 14 may be inserted between the top and bottom of the body, the body being made preferably of copper or other sheet metal, that it may not absorb acids used by furriers. The blade is rigid, extends 55 transversely the full width of the body at the front end, and has a blunt edge. Prefer-

ably the sides of the body slightly diverge toward the rear, in order to give the desired width to the tool, a less width at the front sufficing to provide a blade of sufficient 60 length.

By the described form the tool can be held in the hand and operated without cramping the fingers, the flat under side being sufficient for firm gripping by the thumb, while the curved and downwardly inclined top affords the necessary resistance to any tendency of the fingers to slide rearwardly in the firm gripping of the tool.

By confining the forward dip or incline 70 to the top, leaving the bottom straight and flat, the body is preserved of substantial thickness, which lessens the tendency of the fingers to be cramped in order to effect a firm grip, the curvature, desirable and important for the gripping of the fingers, not being required at the bottom, since the engagement of the thumb with the bottom is largely a direct vertical pressure, while on the other hand, the fingers in gripping will 75 have a tendency to slip backward and become cramped, the tendency being obviated by the described formation of the top.

In using the device for instance by a furrier, the tool is tilted upward at a sufficient 85 angle to the table on which the piece of fur is spread, to cause the lower angle of the blunt edge of the blade to have the desired scraping action. A similar position will be given the tool when scraping wall paper, a 90 butcher's block, or the like.

In ironing or smoothing down a seam in a piece of fur, or a skin, the tool is brought with the bottom surface more nearly parallel with the table and at only a slight angle 95 thereto, sufficient for the movement of the thumb, the rigidity of the blade and its blunt front edge enabling it to successfully iron down the seam without employing a special iron as at present in addition to the scraper.

It is to be understood that the sides 10^a of the body are closed, the sides serving to brace the top and bottom against flexion.

Having thus described my invention, I claim as new, and desire to secure by Letters 105 Patent:

1. A tool of the kind described, consisting of a sheet metal body thickened vertically at its rear end, and decreasing in thickness to the front end, the body at the back being 110 broad to extend substantially the full width of the hand of the user, and of decreasing

- width toward the front, the rear end being rounded vertically and merging in curved lines with the top and bottom, the said top and bottom presenting broad surfaces extending from the front to the back end and the top being concaved longitudinally and inclining toward the bottom from rear to front, the concaved top presenting a gradual curve extending from the rounded back to 10 near the front end; there being a rigid blade ranging across the front end of the body at the juncture of the top and bottom and directly secured to the body between the sheet metal top and bottom.
- 15 2. A tool of the kind described, consisting of a body thickened vertically at its rear end and decreasing in thickness at the front end, the body at the back being broad to extend substantially the full width of the hand of 20 the user, the rear end of the body being

rounded vertically and adapted to bear against the palm of the hand, the top and bottom presenting broad surfaces extending from the front to the back end, and the top being concaved longitudinally and inclining 25 from the rear to the front, the concavity of the said top terminating at the rear end adjacent to the rounded back and terminating forwardly adjacent to the front end of the body; there being a rigid blade ranging 30 across the front end of the body at the juncture of the top and bottom.

In testimony whereof I have signed my name to this specification in the presence of two subscribing witnesses.

EDWIN C. WORNS.
